UNITED STATES PATENT OFFICE.

ALBERT MARKS, OF NEW BRITAIN, CONNECTICUT.

CHECK-WRITING MACHINE.

1,176,389.

Specification of Letters Patent. Patented Mar. 21, 1916.

Application filed May 26, 1915. Serial No. 30,498.

To all whom it may concern:

Be it known that I, ALBERT MARKS, a citizen of the United States of America, residing at New Britain, Connecticut, have invented a new and useful Check-Writing Machine, of which the following is a specification.

My invention relates to machines for imprinting words, letters, numbers or other characters upon strips of paper, for instance, checks and notes and preferably so as to prevent alterations.

The main object is to provide a relatively inexpensive but strong and reliable mechanism which can be readily operated and which will indelibly impress upon a check the words, letters, numbers or characters as required.

Another object is to automatically feed the check through the machine as the impression is made so as to avoid superposition of the impressions.

Another object is to cut the impression and ink it so that it cannot be erased or altered.

Another object is to provide an easy and convenient method of replenishing the ink supply.

Another object is to retract the inking device so as to permit free movement of the impression device.

One form of mechanism embodying my invention is illustrated in the accompanying four sheets of drawings and will be described in detail hereinafter. In this form of construction the check is supported and guided on the base between gages which are adjustable for checks of different widths and different arrangement of blank spaces.

The words, numbers or other characters are formed as cutting teeth on the surface of the segment of a sphere. This segment is adapted to be rotated about one axis to set it for the desired word, number or character. The segment is oscillated about a horizontal axis at right angles to the setting axis for the purpose of passing the impression teeth over the face of the check. A co-operating toothed cutting roller is mounted

beneath the base and brought up against the bottom of the check as the impression segment is rocked on its horizontal axis. The coaction of the impression segment teeth and the teeth of the cutting roller forms the impress in the check and carries it forward

at the same time. When the segment is released it is automatically brought back to its normal position by a spring. During the return movement of the impression segment the lower cutting roller is depressed so as to leave the check free. A friction device is provided for yieldingly holding the check against movement, the tension however is not sufficient to prevent the forward feed of the check during the impression action. An inking roller is provided to engage the teeth of the impression segment as the segment is oscillated. This inking roller is automatically retracted to clear the setting handle of the impression segment. The tension device and the inking roller are both carried by a bridge which is adapted to be moved away from the impression segment so as to facilitate access to the inking roller and other parts.

Figure 1, is a plan view of the entire machine in its normal position of rest. Fig. 2, is a front elevation and partial vertical section on the plane of the line 2-2 of Fig. 1. Fig. 3 is an end elevation and partial vertical section on the plane of the line 3-3 of Fig. 1. Fig. 4, is a vertical section and elevation on the plane of the line 4-4 of Fig. 1 showing the spring for returning the impression segment to its normal position of rest. Fig. 5 is a vertical section on the plane of the line 5-5 of Fig. 1, showing the ratchet connection between the operating shaft and the lower check engaging roller. Fig. 6, is an end elevation and partial vertical section on the plane of the line 6-6 of Fig. 1 showing the parts in the position near the end of the impression stroke. Fig. 7, is a detail edge view of the impression segment and partial section on the plane of the line 7-7 of Fig. 8. Fig. 8, is a view of the underside of the impression segment. Fig. 9, is a fragmentary detail view and partial section on the plane of the line 9-9 of Fig. 2 showing the connection between the operating shaft of the impression segment and the device for operating the lower impression roller. Fig. 10, is a detail perspective view showing the check tension device and the inking roller and the supporting parts. Fig. 11, is a detail perspective view of the tension device alone. Fig. 12, is a detail perspective view of the cam and ratchet member forming the operating connection between the shaft of the impression segment

and the arm for raising the lower impression roller. Fig. 13, is an enlarged view showing one of the impression sectors of the impression segment.

- 5 The base 15 serves as a supporting surface for the check and carries all the parts of the mechanism. Gages 16, 16 are provided for the edges of the check and each of these preferably has a slotted extension 10 16' and a screw 17 for clamping it in adjusted position. A finger 18 is also provided to hold down the check near the impression position. A tension device 19 rests on the face of the check and is preferably pressed downward by a spring 20 so as to frictionally hold the check and prevent it from accidental displacement. This tension device may be retracted by a finger piece 21.
- 20 The impression segment 25 has a number of words, characters or numbers 30 cut in sectors of its face as sharp teeth. This segment is mounted on a pin 26 in the yoke 27 and has an operating knob 28. The back 25 of the segment has a plurality of recesses 29 corresponding with the impression faces 30. A spring pressed ball 31 is adapted to engage in these recesses so as to yieldingly hold the segment in its appropriate position.
- 30 Indicating characters are provided on the upper face of the segment 25 corresponding with the impression faces. The segment is preferably surrounded by a casing 32 for protection and this casing is provided with 35 an indicating opening 33 for displaying the character whose impression face is in the operative position. In Fig. 1 the letter "H" is displayed indicating that the impression sector having the word "Hundred" is in position for impressing the check. It will be noted that the indicating character is diametrically opposite to the impression sector which it represents. The yoke 27 has a stud shaft 34 supported in a 40 post 35. A handle 36 is secured to the end of this stud shaft 34 for oscillating the impression segment in one direction. The edge 37 of the base acts as a stop against the forward movement of the handle 36 45 and the pin 38 acts as a stop for the shoulder 39 in the opposite direction. The impression segment is automatically returned to its normal position by a spring 40, one end of which bears against the stationary pin 41 and the other end of which 50 engages the lug 42 on the yoke of the impression segment.

55 A lower impression cutting roller 45 is carried by the pivoted frame 46 and is normally under tension in a downward direction by the spring 47. This roller 45 is adapted to be raised through the opening 48 by a lever 49. The lever is operated by a cam ring 50 on the stud shaft 34. The 60 stud shaft carries a spring pressed plunger 65

51 which is adapted to engage in notches 52 in the inner wall of the cam ring. The oscillation of the stud shaft 34 rotates the cam ring step by step and thus alternately forces the upper arm of the lever 49 to the right to lift the lower impression roller 45 and then allows the upper arm of the lever 49 to move to the left into one of the notches 53 so as to permit the spring 47 to retract the lower impression roller on the return of the impression segment 25 to its normal position.

70 The inking of the impression sectors of the segment 25 is accomplished by a felt covered roller 55 across the face of which the impression sector passes as the segment is oscillated. This inking roller 55 is preferably mounted on a readily movable pin 56 in a trough 57 so as to better retain the ink and permit ready replacement of the 80 rollers. It is preferable to retract the inking roller out of the path of the setting knob 28 as shown in Fig. 6 so as to avoid smearing the knob. For this purpose the trough 57 is carried by a plate 58 which is 90 pivoted at 59 and normally under tension of the spring 60. This plate 58 is provided with a projecting shoulder 61 adapted to be engaged by the cam face 62 on the yoke 27 of the impression segment. An inclined 95 cam-like shoulder 63 may be provided for engaging the end of the handle of the pin 56 to work the pin back in case it starts to work loose.

100 For convenience in repair, replacement and attachment the tension device 19 and the inking roller 55 are carried by a bridge piece 65 which may be readily moved away from the impression segment. In the form shown this bridge piece is pivoted at 66 and 105 provided with a catch at 67 for holding it in position. When the catch is released the bridge piece and attached parts may be swung away from the impression segment.

110 By withdrawing the knob 28 the impression segment member may be removed for any desired purpose and a new one with words and characters in any language or style of type substituted. In Figs. 6 and 7 the spindle 26 on which the impression member is mounted, is shown provided with a pin 26' engaging in a key slot 25' in the rotary impression member and before the spindle can be withdrawn this pin must be brought into register with a key-way 27' 115 provided for this purpose in the arm of the yoke 27. The ink roller may similarly be 120 removed and a new one of any color substituted.

125 To operate the mechanism in writing a check or other strip or blank, the gages or guides are first set, the paper inserted and the finger piece 21 depressed to allow the blank to be inserted to a proper position. The segment 25 is then set by means of the 130

knob 28 to the desired letter, word or numeral or other character. The handle 36 is then depressed its full extent. This rocks the impression segment 25 and the cam ring 50 moves the lever 49 so as to raise the lower toothed impression roller 45 and cause it to engage the lower side of the check at the same time that the teeth of the impression sector engage the upper side of the check 55 thereby simultaneously cutting the paper and feeding the check forwardly a distance corresponding to the length of the sector on the impression segment. The teeth of the impression sector being inked carry the ink 10 through the paper in the act of cutting so that the word, number or other character is printed on the front and on the back of the check at the same time. At the end of the downward stroke the roller on the upper end 15 of the lever 49 snaps into one of the notches 53 in the cam ring 50 and allows the spring 47 to retract the lower impression roller, thus allowing the paper to fall to its normal position while the impression segment is returned to its normal position under impulse 20 of the spring 40. The impression segment is then reset to the next number, word or character and the operation repeated, the tension members 19 holding the paper during 25 the intervals between the impression steps. By this construction and mode of operation the paper is always fed in accordance with the word or character printed and there is no possibility of the check failing to feed or an impression being duplicated except by intention.

What I claim is:—

1. In a machine of the character described, an oscillating impression member, an inking device, a pivoted support therefor, and a cam movable with said impression member and engaging said pivoted support in the oscillating movement of the impression member for retracting said support.

45 2. In a machine of the character described, a swinging impression member, a swinging inking roller, a removable pivot pin for said roller, and a cam positioned to be engaged by the end of said pin in the swinging movement of said inking roller.

50 3. In a machine of the character described, a movable impression member having a setting knob, an inking roller disposed in the path of movement of said setting knob, a guard plate for said roller, and means for retracting said inking roller automatically out of the path of the knob as the knob passes by the same.

4. In a machine of the character described, 60 a movable impression member having a setting knob, an inking roller disposed in the path of movement of said setting knob, and means for retracting said inking roller automatically out of the path of movement of the knob as the knob passes by the same.

5. In a machine of the character described, a base provided with an upstanding shaft support, a shaft above the base, journaled in said support on a horizontal axis, a printing wheel journaled on said shaft on an axis at a right angle to the axis of said shaft and provided with printing faces on the rim thereof arranged as arcs of circles described about the axis of the shaft as a center, an impression member on the base coöperating 70 with the printing faces of said printing wheel, means for rotating the printing wheel on its axis to carry a selected printing face to the lowermost side of the wheel and means for rocking the shaft to carry the selected 75 printing face into coöperative relation with the impression member.

6. In a machine of the character described, a base provided with an upstanding shaft support, a shaft above the base, journaled in 80 said support on a horizontal axis, a printing wheel journaled on said shaft on an axis at a right angle to the axis of said shaft and provided with printing faces on the rim thereof arranged as arcs of circles described 85 about the axis of the shaft as a center, an impression roller journaled on the base on an axis parallel to the axis of the shaft, means for rotating the printing wheel on its axis to carry a selected printing face to the 90 lowermost side of the wheel and means for rocking the shaft to carry the selected printing face into coöperative relation with the impression roller.

7. In a machine of the character described, 100 a rotatably supported impression member, a supporting shaft journaled on an axis parallel to the axis of rotation of the impression member, an impression wheel journaled on the supporting shaft at an angle 105 to the axis of the shaft, printing faces on the rim of said printing wheel disposed on arcs drawn from the axis of the shaft as a center and arranged to be carried by rotation of the wheel on its axis into a plane of 110 engagement with the rotatable impression member, means for rotating the impression wheel to select the printing faces desired and means for rotating the shaft to carry the selected printing face into impression-making engagement with the impression member.

8. In a machine of the character described, 115 a rotatably supported impression member, a supporting shaft journaled on an axis parallel to the axis of rotation of the impression member, an impression wheel journaled on the supporting shaft at an angle 120 to the axis of the shaft, printing faces on the rim of said printing wheel disposed on arcs drawn from the axis of the shaft as a center and arranged to be carried by rotation of the wheel on its axis into a plane of 125 engagement with the rotatable impression member, means for rotating the impression member, 130

- wheel to select the printing faces desired, means for rocking the supporting shaft a limited distance to carry the selected printing face into impression-making engagement with the impression member and back to initial position free of the impression member and means for automatically separating the impression member and printing wheel at the end of the impression-making engagement.
9. In a machine of the character described, a pivotally supported yoke having spaced supporting arms, a printing wheel journaled between said arms on an axis at an angle to the pivotal axis of the yoke, printing faces on the rim of said wheel disposed on arcs drawn from the pivotal axis of the yoke as a center, an impression member arranged to be engaged by the printing faces of the printing wheel, means for rotating the printing wheel on its axis to bring selected printing faces into the plane of engagement with the impression member and means for rotating the yoke on its pivotal axis to carry the selected printing face into impression-making engagement with the impression member.
10. In a machine of the character described, a pivotally supported yoke having spaced supporting arms, a printing wheel journaled between said arms on an axis at an angle to the pivotal axis of the yoke, printing faces on the rim of said wheel disposed on arcs drawn from the pivotal axis of the yoke as a center, an impression member arranged to be engaged by the printing faces of the printing wheel, means for rotating the printing wheel on its axis to bring selected printing faces into the plane of engagement with the impression member and means for rotating the yoke on its pivotal axis to carry the selected printing face into impression-making engagement with the impression member.
11. In a machine of the character described, a pivotally supported shaft carrying spaced supporting arms, a printing wheel journaled between said arms on an axis at an angle to the pivotal axis of the shaft, printing faces on the rim of said wheel disposed on arcs drawn from the pivotal axis of the shaft as a center, an impression member arranged to be engaged by the printing faces of the printing wheel, means for rotating the printing wheel on its axis to bring selected printing faces into the plane of engagement with the impression member and a handle connected with one end of the shaft for rotating the shaft on its pivotal axis to carry the selected printing face into impression-making engagement with the impression member.
12. In a machine of the character described, a rotatably mounted supporting shaft, a printing wheel journaled on said shaft at an angle to the pivotal axis of the shaft, printing faces on the rim of said wheel disposed on arcs drawn from the pivotal axis of the shaft as a center, an impression member arranged to be engaged by the printing faces of the printing wheel, means for rotating the printing wheel on its axis to bring the selected printing faces into the plane of engagement with the impression member and means for rotating the shaft on its pivotal axis to carry the selected printing face into impression-making engagement with the impression member.
13. In a machine of the character described, a rotatably mounted supporting shaft, a printing wheel journaled on said shaft at an angle to the pivotal axis of the shaft, printing faces on the rim of said wheel disposed on arcs drawn from the pivotal axis of the shaft as a center, an impression member arranged to be engaged by the printing faces of the printing wheel, means for rotating the printing wheel on its axis to bring the selected printing faces into the plane of engagement with the impression member, a stop limiting rotation of the shaft in one direction to a position wherein the printing faces on the printing wheel are disengaged from the impression member, yielding means for normally holding the shaft rotated into said position of inaction and operating means connected with the shaft for rocking said shaft in the opposite direction to carry the printing faces selected into printing engagement with the impression member.
14. In a machine of the character described, a base, a shaft rotatably supported on the base, a printing wheel journaled on said shaft at an angle to the axis of the shaft, a cam ring pivotally engaged on the shaft, a pawl and ratchet connection between the shaft and said cam ring, a bell crank pivoted on the base having an up-standing arm engaging said cam, and an impression member engaged by the other end of the bell crank and adapted to be carried thereby into printing engagement with the printing wheel.
15. In a machine of the character described, a pivotally mounted shaft, a yoke mounted on one end of said shaft having spaced supporting arms, a printing wheel removably engaged between said arms, a spindle at right angles to the axis of the shaft and provided with an operating finger-hold at one end, said spindle being removably keyed to the printing wheel for manipulating the same and whereby upon removal of said spindle, different printing wheels may be substituted, means for rotating the shaft

and yoke carried thereby and an impression member coöperating with the printing wheel.

16. In a machine of the character described, a base, an upstanding support on said base, a shaft journaled in said support, spaced longitudinally extending arms carried by said shaft, a printing wheel engaged between said arms, and an operating spindle 10 pivoted in said arms and connected with said printing wheel, printing faces on said printing wheel disposed on arcs described with the axis of the shaft as a center, and an impression roller journaled on the base 15 in position to be engaged by the printing faces of the printing wheel.

17. In a machine of the character described, a pivotally mounted support, a printing wheel journaled on said support 20 on an axis disposed at an angle to the axis of the support, an operating finger-hold on one side of said printing wheel, an inking device yieldingly supported adjacent said printing wheel, an impression member arranged to coöperate with the printing wheel, means for rocking the support to carry the printing wheel into operative engagement with the impression member and means on the pivoted support engaging the 25 inking device in the rocking movement of said support to force said inking device out of the path of movement of the finger-hold on the printing wheel.

18. In a machine of the character described, a base, a printing wheel supported above the base, an impression member on the base coöperating with said printing wheel, a guide-way extending across the base beneath said printing wheel, a bridge-piece pivoted to the base at one side of the guide-way, and extending above the guide-way across to the opposite side thereof, a catch detachably holding said bridge-piece in position extended across the guide-way, 45 and tension fingers yieldingly pivoted on the bridge-piece projecting into the guide-way, said tension fingers being provided with an exposed finger-piece for operating the same.

19. In a machine of the character described, a base, a printing wheel supported above the base, an impression member on the base coöperating with said printing wheel, a guide-way extending across the 55 base beneath said printing wheel, a bridge-piece pivoted to the base at one side of the guide-way and extending above the guide-way across to the opposite side thereof, a catch detachably holding said bridge-piece in position extended across the guide-way, tension fingers yieldingly pivoted on the bridge-piece projecting into the guide-way, said tension fingers being provided with an exposed finger-piece for operating the same, 60 and an inking device yieldingly supported

on said bridge-piece in position to be engaged by the printing wheel.

20. In a machine of the character described, an impression wheel having toothed cutting faces on the rim thereof extending 70 transversely of the rim and arranged as sectors of a sphere described about the center of the impression wheel, and means whereby said wheel may be rotated on said center to bring different toothed cutting faces into 75 cutting position, and a rocker mounting for said wheel, and an impression member to coact with said cutting faces one at a time.

21. In a machine of the character described, a base, a shaft rotatably supported 80 on said base, a printing wheel carried by said shaft, a cam ring loosely engaged on said shaft, means for oscillating the shaft, a pawl and ratchet connection between said shaft and the cam ring whereby in the oscillating movement of said shaft in one direction the cam ring will be shifted, an impression member mounted on said base for movement toward and away from the printing wheel and a lever pivoted on the base 90 operatively engaged by the cam ring at one end and having an operating connection with the impression member at its opposite end.

22. In a machine of the character described, a supporting yoke having substantially parallel side arms, a rocking support for said yoke, a spindle journaled in said arms at right angles to the axis of said rocking support, a printing wheel engaged 100 on said spindle between said arms having type faces on the rim thereof and holding recesses in the face adjoining one arm of the yoke, a yielding detent mounted in said arm of the yoke engaging in said recesses to hold said printing wheel in its adjusted position and a finger hold on the end of the spindle for turning said spindle and printing wheel against the tension of the yielding detent.

23. In a machine of the character described, a pivotally mounted support, a printing wheel pivoted on said support on an axis intersecting at a right angle the axis of the pivoted support, transversely extending printing faces on the rim of said wheel disposed as segments of a sphere whose center coincides with the intersection of the axes of the pivoted support and the printing wheel, an impression member moved into 115 engagement with the printing face opposed to said impression member, when the pivoted support is rotated on its axis, means for rotating said pivoted support on its axis and means for rotating the printing wheel on its 120 axis to carry selected printing faces into co-operating relation to the impression member.

24. In a machine of the character described, a pivotally mounted support, a printing wheel pivoted on said support on 130

an axis intersecting at a right angle the axis of the pivoted support, transversely extending printing faces on the rim of said wheel disposed as segments of a sphere whose center coincides with the intersection of the axes of the pivoted support and the printing wheel, an impression member moved into engagement with the printing face opposed to said impression member when the pivoted support is rotated on its axis, means for rotating said pivoted support on its axis, means for rotating the printing wheel on its axis to carry selected printing faces into co-operating relation to the impression member, a guard carried by and movable with the pivoted support covering the inoperative printing faces of the printing wheel and co-operating indicating means carried by said printing wheel and guard for indicating which printing face is in co-operating relation with the impression member.

25. In a machine of the character described, a pivotally mounted support, a printing wheel pivoted on said support on an axis intersecting at a right angle the axis of the pivoted support, transversely extending printing faces on the rim of said wheel disposed as segments of a sphere whose center coincides with the intersection of the axes of the pivoted support and the printing wheel, an impression member moved into engagement with the printing face opposed to said impression member when the pivoted support is rotated on its axis, means for rotating said pivoted support on its axis,

means for rotating the printing wheel on its axis to carry selected printing faces into co-operating relation to the impression member, and means operated in the movement of the pivoted support for carrying the impression member into and out of printing engagement with the printing face.

26. In a machine of the character described, a pivotally mounted support, a printing wheel pivoted on said support on an axis intersecting at a right angle the axis of the pivoted support, transversely extending printing faces on the rim of said wheel disposed as segments of a sphere whose center coincides with the intersection of the axes of the pivoted support and the printing wheel, an impression member moved into engagement with the printing face opposed to said impression member when the pivoted support is rotated on its axis, means for rotating the printing wheel on its axis to carry selected printing faces into co-operating relation to the impression member, means for rocking the pivoted support on its axis in one direction to carry the selected printing face into printing engagement with the impression member, means for automatically carrying the impression member out of printing engagement with the printing face at the end of such printing contact, and means for automatically rocking the pivoted support on its axis in the opposite direction back to a position of rest.
